KEY CASE OR PURSE.

Application filed July 21, 1924. Serial No. 727,194.

This invention relates to key cases or purses and it has more particular reference to that type of device wherein a key clip is anchored to holding means with capacity for rotation about its axis to ensure greater freedom of movement relative to the enclosing case.

In key cases or purses now commonly in use, the key is suspended by a snap clip or hook arranged to swing substantially in a single plane around a central pivot point, and it is the primary object of our invention to provide a more flexible mounting whereby the key is not constrained to swing in any definite plane, but may move—more or less universally—in all directions, thus permitting said key to more easily dispose itself within the key case, and thereby aid the compact aggroupment of a collection of 20 keys.

Another object of this invention is to provide a novel form of engaging means or clip which may be readily removed from the holder with a key attached, thereby permitting withdrawal with facility, or replacement within the case with a minimum expenditure of effort and time.

A further object of this invention is to provide a novel form of support, from which 30 the key clips or hooks are suspended, that affords greater longitudinal movement relative to the key case while permitting the keys to automatically stagger themselves and assume positions wherein they will be closely compacted.

A still further object of this invention is to provide a rugged and substantial key case or purse, combining all the above mentioned 40 features, which is of a character lending itself to economical production.

With the foregoing objects and attendant advantages in view, our invention consists essentially in certain features of construction, the combination and arrangement of parts hereinafter fully described, and the novel points whereof are succinctly stated 45 by the subjoined claims.

In the further disclosure of this invention, reference will be made to the accompanying sheet of explanatory drawings, illustrative of one practical embodiment thereof, chosen from other possible forms as best exemplifying the novel features and inherent advantages, said sheet of drawings

constituting a part of this specification, and in which like reference numerals designate the same or corresponding parts in all the views.

Fig. I is a plan view of a key case constructed in accordance with this invention, the same being shown open or unfolded with some of the key anchorages in different positions.

Fig. II is a side view looking to the left hand of the preceding figure.

Fig. III is a broken perspective view exemplifying the manner in which an individual key and attached clip may be removed from—or attached to—the holder member.

Fig. IV is a perspective view of one of the individual key clips or hooks.

Fig. V is a fragmentary perspective view, to an enlarged scale, illustrating the connection between the key clip and holder whereby freedom for longitudinal movement obtains; and,

Fig. VI is a fragmentary sectional view showing the positions the key clip or hook assumes for removal from, and connection to, the holder.

Referring more particularly to the drawings the reference numeral 7 designates the case or purse made from a blank of flexible material adapted for folding on lines or creases 8, 8 to form a body portion 9, with closure flaps 10, 10 arranged to be secured in overlapped relation by means of a conventional snap fastener 11.

A metal holding plate 12 is conveniently secured by gromets 13, or other appropriate means, at one end of the body portion 9. This holding plate 12, it will be noted, is fashioned from a substantially rectangular blank, and provided with a series of parallel elongated slots 14 terminating adjacent one edge 15, while the other ends of said slots are angularly offset and enlarged at 16, for a purpose hereafter fully explained, and as best shown in Fig. VI. The blank formed, as just described, is rolled transversely along parallel lines 17, 18 with the edge 15, aforesaid, brought into abutment on the body portion 9, whereby an elongated lateral loop 19 obtains with the slots 14 vertical thereof.

Each key attaching clip or hook 20—Fig. IV—is preferably formed from a length of round section wire having an in-

herent degree of springiness to afford a holding snap 21, with the free end of the shank 22 spirally coiled upon itself substantially one-and-one-half convolutions to provide a somewhat helico-volute head 23, for entry and withdrawal through the above referred to slot enlargements 16. Hereinafter—and in the claims—the head 23 is designated as helico-volute in order to positively distinguish its formation over what is commonly designated spiralized formation.

In the drawings keys 24 are shown snapped on some of the clips or hooks 20, and for the purpose of explanation distinctive positions thereof are characterized by letters *a*, *b*, *c*, and *d*. Referring more particularly to Figs. I, II and III it will be readily seen that position *a* characterizes the normal or down position of a key 24 and attached clip or hook 20 within the case; *b* indicates an intermediate location with the clip or hook swung out at right angles to the plane of the case 7; and, *c* designates the extreme position assumed by said clip or hook 20 while the key 24 is being manipulated.

In order to remove a clip or hook 20 and attached key 24, said clip or hook is firstly given a further swing through an angle of ninety degrees from position *c* to that designated *d* in Fig. III, or at the back of the body portion 9, whereupon by imparting a half-turn thereto the helico-volute head 23 will be brought into registry with the angular offset 16 of its associated slot 14 and readily withdrawn through the angular enlargement 16 aforesaid. Particular importance is attached to this feature of our invention, inasmuch as it effectively prevents accidental detachment of individual clips 20, when swung over to the position depicted in Fig. II, as said hooks cannot be withdrawn without firstly reversing the normal position of the holding snap 21. Obviously, this manner of removing an individual key 24 is of particular advantage where it is desirable to use said key separated from the rest in the case or purse 7. Apart from the just stated advantage of facility to remove and replace any desired key 24 without disconnection from the clip or hook 20, said key removed retains a characteristic marking so that it will be returned to its proper place; or, in other words the attached clip or hook 20 furnishes a facile means of identification notifying the owner to return the key to the case or purse.

From the foregoing it will be readily understood that by our invention we have provided a key case or purse embodying all the characteristics set forth, with the added advantage of perfect flexibility for each individual key 24 when in use. Furthermore by virtue of the relatively long slots 14 the keys

24 will automatically stagger themselves into compact relation within the case or purse 7 when closed. Still further it will be noted that the manner of attaching the clips or hooks 20 to the holding plate 12 effectively ensures a wide range of free movement that is not constrained to any definite plane but is of a universal character.

Obviously minor detail changes may be made in the form and general construction of our novel key case or purse without departing from the essential features thereof, and, accordingly, we do not limit ourselves to the precise embodiment shown and described, but reserve the right to make such changes as may be circumscribed by reasonable interpretation accorded the subjoined claims.

Having thus described our invention, we claim:

1. In a key case of the type described the combination of a holder member having a portion apertured and retroverted to afford a series of elongated slots having enlarged inner ends, and a complemental series of key-attaching clips having helico-volute heads pivoted in said slots with capacity for individual removal and universal movement over a relatively long range.

2. In a key case of the type described the combination of a holder member having a portion apertured and retroverted to afford a series of elongated slots terminating adjacent one edge with offset enlargements, and a complemental series of headed key-attaching clips universally anchored in said slots by helico-volute heads with provision for individual removal and replacement through the enlargements aforesaid.

3. In a key case of the type described the combination of a holder member having a portion apertured and retroverted to afford a series of elongated slots having enlargements at their inner ends, and a complemental series of individually removable key-attaching clips universally anchored in said slots, each said clip being formed from a length of round-section wire to afford a snap and a helico-volute head fabricated by spiraling the free end of the shank upon itself.

4. In a key case of the type described the combination of a holder member having a portion apertured and retroverted to afford a series of elongated slots having enlarged offset inner ends, and a complemental series of individually removable key attaching clips universally anchored in said slots, each said clip being formed from a length of round-section wire to afford a snap and a helico-volute head fabricated by spiraling the free end of the clip shank upon itself with substantially one-and-one-half convolutions.

5. In a key case of the type described the

- combination of a holder member having a portion apertured and retroverted to afford a series of elongated slots terminating adjacent the folded over portion with aligned angularly-offset enlargements, and a complementary series of key-attaching clips having integral helico-volute heads freely anchored in said slots with capacity for individual removal and insertion through the offset enlargements aforesaid. 6. In a key case of the type described the combination of a holder member having a portion apertured and retroverted to afford a series of elongated slots terminating adjacent the folded over edge with aligned angularly-offset enlargements, and a complementary series of key-attaching clips having helico-volute heads freely anchored in said slots, individual clips being removable by transfer into registration with the angularly offset enlargements and lateral manipulation relative thereto. 7. In a key case of the type described the combination of a holder member having a portion apertured and retroverted to afford a series of elongated slots provided with aligned angularly-offset enlargements at the inner ends thereof, and a complementary series of helico-volute headed key attaching clips adapted for individually assembly in and temporary removal therefrom. 20 25 30
- In testimony whereof, we have hereunto signed our names at Allentown, Pennsylvania, this 15th day of July, 1924.
